UNITED STATES PATENT OFFICE

HOWARD L. STOVER, OF WILLIAMSPORT, PENNSYLVANIA

GARMENT HANGER

Application filed July 5, 1928. Serial No. 290,587.

This invention relates to improvements in clothes hanging apparatus.

The primary object of this invention is the provision of a clothes hanger of a novel construction, which may have an improved detachable and movable connection upon a support to be mounted upon a wall, by means of which the clothes hangers may be compactly arranged along the wall according to the space desired, and thus taking care of garments having various thicknesses, so that they may be compactly arranged in close conformity to each other, thus conserving space.

15 A further object of this invention is the provision of an improved clothes hanger, having a conventional shaped garment supporting body with improved means for supporting the same in an outstanding relation 20 from a vertical wall or support.

Other objects and advantages of this invention will be apparent during the course of the following detailed description.

In the accompanying drawing, forming 25 a part of this specification, and wherein similar reference characters designate corresponding parts throughout the several views,

Figure 1 is a perspective view showing an 30 improved support mounted upon a wall board, showing the manner in which the improved hangers are mounted in a compact relation thereon.

Figure 2 is a cross sectional view taken 35 at the supporting attachment of the hanger upon a wall.

Figure 3 is a view of the details illustrated in Figure 2, showing the manner in which the improved hanger may be assembled or 40 detached with respect to the supporting plate or member.

In the drawing, wherein for the purpose of illustration is shown only a preferred embodiment of the invention, the letter A 45 may generally designate the improved hanger, which is adapted to be mounted upon a novel supporting plate or member B attached to a wall board C or the like.

50 The hanger A preferably comprises a garment supporting body 10, having an up-

wardly and laterally extending supporting arm structure 11 connected therewith for attachment to the plate B.

The improved hanger A is preferably formed of wire, although it may be formed otherwise if desired. It is preferably made of a single piece of wire, bent into the form described.

In the preferred construction of the hanger, the garment supporting body 10 is formed by doubling the length of wire, of which the hanger is formed, intermediate its ends to provide a straight supporting bar 15, with the diagonally converging shoulder bars 16 and 17 bent at the ends of the bar 15, and twisted together at 18 at their proximate ends, above the bar 15. One end of the wire piece of which the hanger is formed is continued upwardly at 20, in a line preferably at right angles to the supporting bar 15, extending upwardly a sufficient distance to permit the hanger body to depend for efficiently receiving clothes. In the ordinary instance the upwardly extending piece 20, which forms part of the arm structure 11, is about three inches in length. This end of the piece of material from which the hanger is formed is then extended horizontally laterally in the plane of the hanger body 10, providing an arm proper 21 55 which is arranged at right angles to the piece 20. The other end of the wire after forming the twist 18 is extended diagonally upward to provide a diagonal brace 23 extending from the twisted section 18 to adjacent the free end of the arm proper 21, where the wires of the portions 21 and 23 are twisted together at 27.

The free ends of the wire forming the hanger, and forming the outer end structure of the arm construction 11, are then arranged in a bifurcated U-shaped relation in the same plane as the hanger body 10, but at a point laterally beyond the adjacent end 30 of the hanger body 10. Thus, from the twisted section 27 the wires are bent upwardly and downwardly at 33 and 34 respectively, and bent in right angled relation at 37 and 38; the portions 37 and 38 being relatively long and lying in a plane parallel with the hanger 60

body and being parallel with the arm proper 21 at the same distance from each side of the axis of the arm proper 21.

The wires at the free ends of the portions 37 and 38 are respectively bent upwardly and downwardly at 40 and 41, in the same plane as the U-shaped portion of which the arms 37 and 38 are a part, and at the free ends of the portions 40 and 41, the supporting plate engaging feet 46 and 47 are provided, extending in right angled relation to the plane of the U-shaped bifurcated end of the arm structure 11; said supporting plate engaging feet 46 and 47 being of approximately the same length, that is, about one inch in length, and extending parallel to each other, and offset by the portions 40 and 41 above and below their respective connected arm portions 37 and 38.

It is thus apparent that the supporting body 10 is provided with a well braced and fixed rigid laterally extending arm structure 11, thereabove, the parts of which are formed to lie in the same plane as the garment supporting body 10; the arm structure 11 at the free ends thereof having supporting plate attaching feet.

The supporting member or plate B is an elongated metal strip, consisting of a back body plate 50, having a lower flange 51, of a double thickness, bent transverse to the plate body 50, at an angle of slightly less than 90°. An inverted J-shaped flange 52 is provided along the top edge of the plate body 50, providing a downwardly facing socket 53. The body 50 at spaced intervals, is provided with openings for receiving attaching screws 52a, by means of which the plate B may be applied to a wall, or to the supporting rail C which is ordinarily applied to the walls within a closet for receiving hooks and like hangars.

As to the application of the improved clothes supporting device A upon the supporting plate B, the upper attaching foot 46 is first slipped into the downwardly facing socket 53, and when fully slipped upwardly therein the other foot 47 is moved towards the plate B to rest upon the rail 51. The latter is tilted upwardly slightly at an angle and is resilient to a certain extent for holding the feet 46 and 47 of the hanger firmly in place against vertical movement upon the supporting rail or plate B. The mode of attachment is shown in Figure 3, with the complete attachment as shown in Figure 2. In this position of parts the arm structure 11 of the hanger A extends transverse from the plate A in a longitudinally slidable relation and detachably connected therewith. At the lower ends of the outwardly extending arm structure 11, of course, is positioned the garment hanger body 10, which is supported by the arm structure 11 in a spaced relation from the

wall, for receiving garments in the usual relation.

A notable feature of the invention is the economy with which the same may be manufactured. The garment hanger is formed of a single length of wire and bent to form as shown, and provides a very durable and efficient supporting device which may be moved in a plane longitudinally of the supporting rail B, so that the hangers may be spaced, say, one inch apart if supporting thin garments, such as ladies' dresses. Thus, with a supporting rail B two feet in length, twenty-four of such hangers may be accommodated. The conservation in space within a small closet will be readily apparent. A very desirable feature of the hanger construction is the fact that the hangers may be moved towards and away from each other, in parallel planes, with facility, and the hangers may be spaced apart to accommodate garments of various thicknesses. This does away with lost space within a closet, such as is the case where hangers are adapted to be supported upon vertical walls by means of fixed hangers or brackets.

Various changes in the shape, size, and arrangement of parts may be made to the form of invention herein shown and described, without departing from the spirit of the invention or the scope of the claims.

I claim:

1. As an article of manufacture a garment hanger supporting rail consisting of an elongated supporting body having a lower substantially right angled transverse flange and an upper socket flange with a socket opening directly facing the lower flange.

2. In a garment hanging structure of the class described a wall supporting rail having a lower transverse flange and an upper socket flange with a socket facing the lower flange, a garment hanger, an arm connected with the garment hanger extending beyond the garment hanger, and an attaching structure on the free end of the arm including a transverse foot for slidable reception in the socket of the socket flange and a foot for resting on the lower flange of the said rail when the other foot is in the socket of said socket flange.

3. As an article of manufacture a garment hanger comprising a hanger body, an arm rigidly connected with and above the hanger body and extending beyond the hanger body, said arm at the free end thereof having spaced wire portions with offsets above and below the wire portions, said offsets having attaching feet at the free ends thereof transverse to the plane of the hanger body.

4. In a garment hanging structure an elongated supporting rail including a body having a lower transversely extending supporting flange and an upwardly disposed socket providing flange having a downwardly opening socket facing the first mentioned

flange, a hanger body having a laterally extending arm projecting to a point beyond the hanger body, said arm at its free end spaced and disconnected from the hanger body having a pair of spaced feet one of which rests on the lower flange and the other of which releasably rests in the socket of the rail.

5. As an article of manufacture a wire garment hanger comprising a single length of
10 wire bent intermediate its ends to provide a conventional coat hanger body which includes a lower horizontal bar and wire portions extending upwardly from the ends of the horizontal bar which are twisted together
15 substantially centrally above the horizontal bar, the wire from said twisted portions extending upwardly in right angled relation to the horizontal bar and at its upper end being horizontally laterally turned in the plane
20 of the hanger body and extending to a location beyond the end of the hanger body and in the same plane therewith, the wire from said twisted location centrally of the hanger body being also extending diagonally up-
25 wardly toward the free end of said arm and being twisted into a right connected bracing relation with the free end of said arm, the outer ends of said wire being spaced and pro-
30 vided with laterally offset resilient yieldably supported and attaching feet.
